UNITED STATES PATENT OFFICE.

FRANK B. SNYDER, OF LANCASTER, PENNSYLVANIA, ASSIGNOR OF FORTY-NINE PER CENT TO JOHN H. HALLES AND OF FIFTY-ONE PER CENT TO R. L. PETERMAN, BOTH OF LANCASTER, PENNSYLVANIA.

DRAFT APPLIANCE FOR FURNACES.

Application filed June 3, 1926. Serial No. 113,496.

This invention relates to improvements in draft appliances for furnaces and more particularly to a draft appliance for heating furnaces in which soft coal is to be burned, and one of the objects of the invention is to provide a draft appliance of such construction that the products of combustion will be conducted from the furnace in a steady and uniform draft or flow, thus effecting substantially complete combustion of the fuel and obviating the dense smoke which is usually produced in burning fuel of the character referred to.

Another object of the invention is to so construct the draft appliance that there can be no back draft into the furnace so that the perfect and complete combustion of the fuel will not be interfered with and no gaseous products of combustion or smoke will issue from the furnace to cause annoyance to those residing in the house in which the furnace is installed.

Another object of the invention is to provide means whereby the products of combustion, as they are delivered into the chimney, will be divided into two separate currents and in such a manner as to tend to establish a swirling of the currents a short distance above their point of delivery into the chimney flue, thus setting up a constant and uniform draft through the appliance and insuring of more complete and perfect combustion of the fuel.

Another object of the invention is to so construct the device that the delivery of the products of combustion from the burning fuel will be so controlled, automatically, as to insure of even burning of the fuel so that it will be consumed uniformly and the best results thus obtained.

In the accompanying drawings:

Figure 1 is a view in side elevation of the appliance embodying the invention installed in connection with a furnace and chimney.

Figure 2 is a vertical transverse sectional view in detail, taken substantially on the line 2-2 of Figure 1, looking in the direction indicated by the arrows.

Figure 3 is a vertical longitudinal sectional view through the flue pipe of the appliance, the damper being shown partly open.

Figure 4 is a vertical longitudinal sec-

tional view through the baffle section of the appliance.

In the drawings, the numeral 1 indicates in general an ordinary heating furnace and the numeral 2 indicates the ordinary chimney having the usual flue 3. As is well known, the common practice is to lead a flue of relatively large diameter from the furnace to the chimney and deliver the products of combustion into the flue 3, the delivery or discharge end of the flue pipe being fitted into the usual opening in the chimney wall and terminating within the opening. I have found, however, that this common practice is disadvantageous where soft coal is to be consumed and that, in fact, even where hard coal is employed, better results may be obtained by a draft appliance constructed in accordance with the present invention and designed to prevent any back draft from the chimney flue. The appliance embodying the invention comprises two units, one being a draft unit and indicated in general by the numeral 4, and the other a baffle unit and indicated in general by the numeral 5. The draft unit 4 comprises a section of flue pipe including a straight length 6, elbows 7 and 8, and a short upwardly extending branch 9 between the elbows. One end of the portion 6 of the unit 4, namely the end opposite the end at which the elbow 7 is located, is fitted to the thimble 10 which is usually found on heating furnaces, and this unit takes the place of the flue pipe usually fitted to the said thimble. A damper 11 of the ordinary type is mounted in the portion 6 of the draft unit near the elbow 7 and under normal conditions this damper will be left substantially closed although, as is usual, it is provided with two small sized draft openings 12 to provide for a restricted draft.

The damper 11 is, in fact, only employed in full open position when a fresh fire is being built in the furnace and, at other times, will be adjusted to nearly closed position or completely closed position. A draft pipe 13 is arranged to extend from the attached end portion of the part 6 of the draft unit 4 to the back of the elbow 8 and is, therefore, arranged in an upwardly inclined position and serves to conduct the products of combustion, which do not pass through the main

part of the unit, directly to the elbow 8 where they are delivered into one or more lengths of flue piping 14 which, in turn, conduct the products of combustion to the 5 unit 5.

The unit 5 comprises a hollow cylindrical body 15 which may be formed from a length of flue piping or may be cast, either as desired, and this body is fitted into a thimble 16' arranged in the usual manner in the flue opening of the chimney wall and extends at its inner end into the flue 3, the pipe at its other end being connected with the pipe section 14. The body 15, from its 15 free end, is cut away on curved lines, as indicated by the numeral 16, to a point midway between the ends of the body or to such a distance that with the section or body arranged within the chimney in the manner 20 shown in Figure 1 of the drawings, the free end of the body will nearly abut the wall of the chimney flue opposite the wall in which the thimble 16' is arranged, and the lower end of the cut away portion will be located 25 relatively close to the inner end of the said thimble 16'. In this manner, a gradually tapering baffle is provided within the chimney flue, and it will be observed by reference to Figures 1 and 2 of the drawings that the 30 products of combustion are caused to pass upwardly about the edges 16 of the cut away portion or baffle in the manner shown in the said figures by the arrows and, in passing up through the chimney flue, will follow a 35 circling or swirling course, thus creating a considerable draft in the appliance embodying the invention and effecting thorough and perfect combustion of the fuel in the firebox of the furnace without any likelihood of any 40 down draft in view of the fact that the baffle of the unit 5 extends into the chimney flue and constitutes means for effectually preventing such back draft through the member 5. In order to prevent any side draft 45 which might interfere with the discharge of the products of combustion from the baffle unit into the chimney flue, and likewise in order to insure of a separation or division of the products of combustion so as to cause 50 substantially the same volume to flow and escape at either side of the baffle, a vane 17 of sheet metal or any other construction is secured at its upper side at one end to the under side of the narrow end of the baffle 55 provided at the end of the body 15, and the inner end of this vane is secured by rivets or otherwise, as at 18, to the lower side of the member 15 at the lower side of the cut away portion 16, the front and lower edges 60 of the vane 17 extending at right angles to each other as clearly shown in Figure 4, and the upper edge of the said vane being curved downwardly and rearwardly from the attached outer end of the said vane, as indicated by the numeral 19. It will now be

evident that the products of combustion will be caused to separate and flow upwardly at opposite sides of the baffle formed by the cut away portion 16 and these upflowing currents will meet above the baffle and a swirling draft will be established in the chimney flue, effectually preventing any back draft which would result in uneven and imperfect combustion of the fuel in the firebox of the furnace. 75

It will be understood, of course, that the units 4 and 5 are to be placed upon the market and it will be evident that they may be readily adapted to any furnace and to any chimney and connected by the ordinary flue piping, of which any desired length may be used. 80

Having thus described the invention, what I claim is:

1. In a draft appliance for furnaces, a hollow body member for delivering the products of combustion from a furnace to a chimney having a baffle extending beyond its discharge end to obstruct back draft from the chimney, and a vane supported beneath the said baffle and extending from the outer end of the baffle to the said end of the body at the lower side thereof and providing means for causing division of the products of combustion as they are deflected by the baffle. 95

2. In a draft appliance for furnaces, a hollow body member for delivering the products of combustion from a furnace to a chimney having a baffle extending beyond its discharge end to obstruct back draft from the chimney, and a vane supported beneath the said baffle and extending from the outer end of the baffle to the said end of the body at the lower side thereof and providing means for causing division of the products of combustion as they are deflected by the baffle, the upper edge of the said vane being inclined downwardly from the front end of the vane to the rear end thereof. 105

3. In a draft appliance for furnaces, a hollow body member for delivering the products of combustion from a furnace to a chimney having its lower side cut away on downwardly and outwardly curving lines whereby to provide a baffle extending beyond the discharge end of the body to obstruct back draft from the chimney. 115

4. In a draft appliance for furnaces, a hollow body member for delivering the products of combustion from a furnace to a chimney having its lower side cut away on downwardly and outwardly curving lines whereby to provide a baffle extending beyond the discharge end of the body to obstruct back draft from the chimney, and a vane extending beneath the said baffle and in the path of the products of combustion from the discharge end of the body and con- 125 130

stituting means for dividing the products as they are delivered against the baffle.

5. In a draft appliance for furnaces, a draft unit comprising a main flue having an upwardly extending branch, a diagonal flue section extending between the said flue and its branch and communicating at its ends therewith, a damper in the said flue, and a baffle unit comprising a hollow body in communication with the branch of the main flue and having a baffle extending beyond its discharge end.

6. In a draft appliance for furnaces, a draft unit comprising a main flue having an upwardly extending branch, a diagonal flue section extending between the said flue and its branch and communicating at its ends therewith, a damper in the said flue, a baffle unit comprising a hollow body in communication with the branch of the main flue and having a baffle extending beyond its dis-

charge end, and a perpendicularly disposed vane extending beneath the said baffle with its upper edge spaced therefrom.

7. In a draft appliance for furnaces, a draft unit comprising a main flue having an upwardly extending branch, a diagonal pipe section extending between the said flue and its branch and communicating at its ends therewith, a damper in the said main flue, a hollow cylindrical flue section in communication with the branch of the main flue having its under side cut away to provide a baffle extending beyond its discharge end, and a vane supported beneath the baffle and constituting means for dividing the products of combustion delivered from the discharge end of the said body and directed against the baffle.

In testimony whereof I affix my signature.

FRANK B. SNYDER. [L. S.]
